UNITED STATES PATENT OFFICE.

TALMA T. GREENWOOD, OF TEMPLETON, MASSACHUSETTS, ASSIGNOR, BY MESNE ASSIGNMENTS, TO CONDIT ELECTRICAL MANUFACTURING COMPANY, A CORPORATION OF MASSACHUSETTS.

ELECTRIC SWITCH.

Application filed October 29, 1920. Serial No. 420,505.

To all whom it may concern:

Be it known that I, TALMA T. GREENWOOD, a citizen of the United States, residing at Templeton, in the county of Worcester and State of Massachusetts, have invented an Improvement in Electric Switches, of which the following is a specification.

This invention relates to oil immersed electric switches especially adapted to carry 10 high values of current; and has for its object generally to improve the construction and operation of a switch of the type set forth and, specifically, to increase the current-carrying and current-interrupting capacity of the switch.

The current carrying capacity of an oil immersed electric switch depends upon the temperature of the switch components and, especially, the oil in which the switch members are immersed. In practice the current carrying capacity of the switch is limited by the rise in temperature of the oil and, other things being equal, the switch in which the oil is maintained at the lowest temperature 25 will carry the greatest value of current. The current interrupting capacity of the switch is also affected by the temperature and usually a switch having a relatively high oil temperature can not safely interrupt as high a value of current as can a switch having a relatively low oil temperature.

The oil receptacle of the switch, especially in switches adapted to carry and interrupt current of relatively high value, is provided 35 with an insulating lining of wood or the equivalent which is interposed between the switch members and the heat dissipating wall of the receptacle to prevent contact of the arc formed upon circuit interruption 40 with the metal of the receptacle. The lining extends over the bottom and upwardly along the side walls of the receptacle to a point above the oil level, although in some cases it may not extend entirely to the surface of 45 the oil. The lining is usually in direct contact with the side walls of the receptacle and is, in fact, a box which fits within the oil receptacle.

The exposed outer surface of the side 50 walls of the receptacle provide practically

the sole means by which heat may be dissipated from the oil in the receptacle. Inasmuch as the lining covers the side walls, the oil cannot come in direct contact with the side walls and, consequently, can not dissipate its 55 heat. The lining serves as a heat insulator as well as an electrical insulator. While the material composing the lining may be more or less porous, especially if the material is wood, and so may become saturated with oil, 60 yet the heat given up to the side walls of the receptacle is negligible, as no effective circulation of oil can take place.

Some linings are spaced from the side walls of the oil receptacle and the space 65 therebetween contains oil but there is no provision for effective circulation of oil from the space within the lining past the side walls and, consequently, there is no substantial dissipation of heat.

In some instances, the level of oil may extend above the top of the lining and thereby be in direct contact with the side walls of the oil receptacle. In this case some heat may be dissipated from the oil but, here again, 75 the arrangement of the lining is such as to prevent effective circulation of the oil for the dissipation of its heat to keep down the temperature of the oil.

In carrying out my invention, I provide 80 an electrically insulating lining the side walls of which are spaced from the side walls of the oil receptacle sufficiently to admit of a practically unrestricted flow of oil therebetween. The oil within the lining is 85 in communication with the cooling space between the lining and the oil receptacle at the top and bottom, whereby to admit of a circulation, by thermal action, of hot oil from the interior of the lining to the space 90 between the lining and oil receptacle. Heat will be dissipated by the side walls of the oil receptacle and the cooled oil will descend down the space between the lining and receptacle and enter the space within the lining and cool the switch members therein disposed. The greater the amount of heat to be dissipated, the more rapid will be the 95 circulation of oil.

A further object of my invention is to 100

provide the oil receptacle constructed as above set forth as an attachment to be applied to existing switches.

Fig. 1 is a transverse section of a switch embodying my invention.

Fig. 2 is a plan view of the oil receptacle embodying my invention, partly in section.

Fig. 3 is a sectional detail of a modified arrangement of oil passages through the lining of the oil receptacle.

Fig. 4 is a plan detail of the structure of Fig. 3.

As here shown the switch embodying my invention comprises the switch frame 10 bearing the stationary switch members 11 provided with contact or arcing members at their lower ends, and the movable switch members 12. Said frame is secured to the supporting structure 13 enclosing the switch 20 operating mechanism 14.

The oil receptacle with which my invention is more particularly concerned is formed with the bottom wall 15 and the vertically extended side walls 16 formed of good heat 25 conducting and dissipating material and is removably secured to the switch frame by the bolts 17 and wing nuts 18.

The electrically insulating lining is herein formed of wood, although other well known 30 insulating materials may be employed, and comprises the bottom wall 20 which preferably rests upon the bottom wall 15 of the oil receptacle, and the side walls 21 which, in accordance with my invention, are spaced 35 from the side walls of the oil receptacle to provide a vertical passage or cooling chamber A down which oil may flow to be cooled. Said side walls 21 may be secured to the bottom wall 20 by the vertically extended strips 40 22 which may be carried by the bottom wall and are dove-tailed in said side walls. Said strips also serve as spacer strips to maintain said passage A and support said walls 21 spaced from the side walls of the oil receptacle whereby to resist displacement upon 45 the occurrence of pressure within the switch due to circuit interruption.

In Fig. 1 the lower edge of the side walls 21 is vertically spaced from the bottom wall 50 whereby to provide a lower communicating passage 23 between the passage A and the main body of oil within the oil receptacle.

Baffle plates 24 and 25 are arranged on both sides of said passage to prevent contact 55 of the arc formed upon opening the switch with the metallic walls of the oil receptacle. Said baffle plates, however, are so arranged as to oppose negligible resistance to the circulation of oil.

The side walls 21 of the electrically insulating lining may terminate a substantial distance below the surface of the oil whereby an equivalent communicating passage equal 60 to the height of the oil above the side walls

will be provided between the main body of oil and the oil in said cooling passage A; or said side walls may extend above the surface of the oil, as in Fig. 3, and a plurality of openings 26 may be formed therethrough near the top and below the surface 70 of the oil to admit of communication between the main body of oil with the top of the body of oil in said cooling passage A.

In Fig. 3 is also shown a modified means whereby the cooling passage A is placed in 75 communication with the lower portion of the main body of oil. In this modification, the bottom wall 20 of the lining is raised above the bottom wall of the oil receptacle to provide an oil passage B therebetween, 80 and said bottom wall 20 is formed with a plurality of openings 27 therethrough by which oil communication is established between said passage A and the main body of oil. A baffle plate extends above said openings and is spaced above said bottom wall to prevent access of the circuit-interrupting 85 arc to the wall of the oil receptacle.

The hot oil within the switch and adjacent the switch members will rise to the top of 90 the oil and enter the passage A either through the openings 26 or over the top of the lining. The relatively cool walls of the oil receptacle will dissipate the heat and cool the oil, and the cool oil will descend 95 in said passage and enter the space enclosed by the lining by means of the openings 23 or 27. The cool oil will then abstract heat from the switch members or other switch components in heat communication with the 100 oil and become heated and again pass through said cooling passage A.

I claim:

1. An electric switch having an oil receptacle formed with heat absorbing and dissipating walls, stationary switch terminals extended into said receptacle and having contact-members supported by their lower ends, an electrically insulating lining disposed within said receptacle between the side walls of said receptacle and said switch terminals, and surrounding said switch terminals and contact members, said lining relatively closely spaced from the side walls of the oil receptacle to provide an oil-cooling passage between the receptacle and lining, and having means to provide for oil flow between the top and bottom portions of said oil-cooling passage and the top and bottom portions of the oil space within said lining, whereby to cool the oil in the receptacle.

2. An electric switch having an oil receptacle formed with heat absorbing and dissipating walls, stationary switch terminals 125 extended into said receptacle and having contact-members supported by their lower ends, an electrically insulating lining dis-

posed within and carried by said receptacle between the side walls of said receptacle and said switch terminals, and surrounding said switch terminals and contact members, said lining relatively closely spaced from the side walls of the oil receptacle to provide an oil-cooling passage between the receptacle and lining, and having means to provide for oil flow between the top and bottom por-

tions of said oil-cooling passage and the top and bottom portions of the oil space within said lining, whereby to cool the oil in the receptacle, and means to secure the receptacle and lining removably to the switch about said switch-members.

In testimony whereof, I have signed my name to this specification.

TALMA T. GREENWOOD.
